(57) **CLAIM**

The ornamental design for a sex massager, as shown and described.

DESCRIPTION

FIG. 1 is a front, right, and top perspective view of a sex massager, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a protrusion.

FIG. 9 is a partial enlarged view of an area labeled 9 in FIG. 1 comprising a handle; and,

FIG. 10 is a partial enlarged view of an area labeled 10 in FIG. 1 comprising a part of a round part.

The broken lines shown in the drawings are included for the purpose of illustrating portions of the sex massager that form no part of the claimed design.

The dash-dot broken lines shown are for the purpose of showing enlarged areas, which form no part of the claimed design.

1 Claim, 10 Drawing Sheets
